UNITED STATES PATENT OFFICE.

MERVIN A. GENSLER, OF YORK, PENNSYLVANIA.

DESIGN FOR A COMB-CLEANER.

42,964.

Specification for Design.

Patented Sept. 3, 1912.

Application filed May 8, 1912. Serial No. 695,999. Term of patent 7 years.

To all whom it may concern:

Be it known that I, MERVIN A. GENSLER, a citizen of the United States, residing at York, Pennsylvania, have invented a new, original, and ornamental Design for a Comb-Cleaner, of which the following is a specification, reference being had to the accompanying drawing, forming a part thereof.

In the drawings, Figure 1 shows a side elevation, and Fig. 2 a plan view of the new design.

As shown, my improved design is composed of a handle *a*, and three prongs, these

prongs having serrated edges and tapering ends and being of the general shape and configuration shown.

I claim:

The ornamental design for a comb cleaner as shown and described.

In testimony whereof, I affix my signature in presence of two witnesses.

MERVIN A. GENSLER.

Witnesses:

MORGAN M. DELLINGER,
MARY M. PETERS.
